UNITED STATES PATENT OFFICE.

LEON R. SMITH, OF PENDLETON, INDIANA, ASSIGNOR TO MOTSINGER DEVICE MANUFACTURING COMPANY, OF PENDLETON, INDIANA, A CORPORATION OF INDIANA.

BRUSH-HOLDER FOR ELECTRIC GENERATORS.

SPECIFICATION forming part of Letters Patent No. 769,195, dated September 6, 1904.
Application filed April 13, 1904. Serial No. 202,926. (No model.)

To all whom it may concern:

Be it known that I, LEON R. SMITH, a citizen of the United States, residing at Pendleton, in the county of Madison and State of Indiana, have invented certain new and useful Improvements in Brush-Holders for Electric Generators, of which the following is a specification.

In the smaller sizes of electric generators, especially of that type in Patent No. 710,597, it has been found desirable to have each brush composed of two or more independent members both for convenience in manufacturing brushes and also for convenience in handling them.

The object of my present invention is to produce a holder for a pair of small brushes.

The accompanying drawings illustrate my invention.

Figure 1 is a central vertical section; Fig. 2, a perspective; Fig. 3, a section on line 3 3 of Fig. 1; Fig. 4, an under plan; Fig. 5, a detail of the contact-piece, and Fig. 6 a detail showing the method of manufacture.

In the drawings, 7 7 indicate a pair of parallel tubes substantially circular in cross-section, the said tubes being made from a single tube 7' (shown in dotted lines in Fig. 6) by inserting a pair of parallel mandrels therein and crushing the initial tube into the form shown in Fig. 6 about said mandrels. I then take a flat substantially circular plate 8, provided with an ear 9, to which a circuit-wire may be attached. Plate 8 has formed therethrough a pair of closely adjacent circular perforations 10 10 of the same size as the external diameter of the tubes 7, and these perforations are connected by a short channel or slot 11 of a size and shape adapted to permit the passage of the neck portion 7", which connects the tubes 7 7. The plate 8 is driven upon or otherwise suitably secured to the tubes 7 7 at an intermediate point, as clearly shown in the drawings. An insulating-bushing 12 is also provided with a pair of axial perforations 13 13 of the same size and arrangement as the perforations 10 and similarly connected by a

short channel 14, so that the bushing can be also slipped upon the tubes 7 7 and secured to the plate 8 by any suitable means, such as 50 screws 19. The open outer ends of the tubes 7 are closed by removable plugs 15, which are held in place by suitable removable means, such as cotter-pins 16. The usual brushes 17 may then be introduced into the tubes 7 and 55 a suitable spring 18 placed between each brush and the plug 15.

I claim as my invention—

1. A brush-holder for electric generators, consisting of, an insulating-bushing provided 60 with a pair of adjacent parallel axial perforations and a connecting-slot, and a pair of tubular brush-holders formed by a single piece of metal and inserted in said perforations of the insulating-bushing. 65

2. A brush-holder for electric generators, consisting of, an insulating-bushing having a pair of parallel axial perforations connected by a slot, a pair of parallel brush-receiving tubes formed of a single piece and inserted in 70 said axial perforations and the slot, and a removable plug for the outer end of each tube. 75

3. A brush-holder for electric generators, consisting of, a plate having a pair of axial perforations, a pair of brush-receiving tubes 75 passing through said perforations, and means for retaining a brush in each of said tubes.

4. A brush-holder for electric generators, consisting of, an electrical conductor having a pair of adjacent perforations, a pair of tubular brush-holders passing through said perforations and electrically connected to said conductor, an insulating-bushing having a pair of axial perforations adapted to receive the brush-holders, and means for retaining a 85 brush in each of said tubes.

In witness whereof I have hereunto set my hand and seal, at Indianapolis, Indiana, this 9th day of April, A. D. 1904.

LEON R. SMITH. [L. s.]
